Patented Nov. 9, 1926.

UNITED STATES PATENT OFFICE.

ALBERT E. MATT, DECEASED, LATE OF STILLWELL, INDIANA; BY ANNA MATT, AD-
MINISTRATRIX, OF STILLWELL, INDIANA.

PACKAGE TIE.

Application filed July 17, 1926. Serial No. 123,232.

This invention relates to package ties and has for its primary object to provide a very simple device for securely tying together a package of papers, envelopes, or like articles without necessitating that the tie string be knotted, said device being capable of easy and quick manipulation in applying the same to a package.

It is another particular object of the invention to provide a device of this character embodying a metal disk having a central button or head provided with spaced oppositely extending tie arms fixed at their outer extremities to the disk, in combination with a tying string permanently connected to one of said arms, said head being provided upon its under side and at opposite points with lugs or projections for binding engagement upon the string when the same is wound about the shanks beneath the head or button.

It is an additional object of the invention to provide a device for the above purpose which may be manufactured at minimum cost, is strong and durable in construction and not likely to tear the papers or envelopes when in its applied position.

With the above and other objects in view, the invention consists in the novel features of construction, combination and arrangement of parts to be hereinafter more fully described, claimed and illustrated in the accompanying drawings, in which,

Figure 1 is a plan view showing my improved package tie applied to a package of envelopes;

Figure 2 is an enlarged sectional view of the device taken on the line 2—2 of Figure 1; and

Figure 3 is a section taken on the line 3—3 of Figure 2.

Referring in detail to the drawing, 5 designates a sheet metal disk, preferably of tin, and nickelized, painted or otherwise provided with surface ornamentation. This disk, as clearly shown in Figure 2, has a body portion 6 of concavo-convex form and at the center of the disk, the same is punched upwardly from the concave face thereof to provide a short annular flange. The straight horizontal marginal portion 8 of the disk may be provided with any desired advertising matter, as indicated in Figure 1. A relatively small circular head 9 is supported above the upwardly struck flange

7 at the center of the disk, by means of spaced, flat, metal shanks 10. These shanks project downwardly at opposite sides of the flange 7 and at a point spaced from the concave face of the disk 5, said shanks are extended outwardly in opposite directions to form supporting arms 11. These arms are soldered or otherwise permanently secured at their extremities to the disk 5 at the junction of the curved body portion 6 thereof with the marginal horizontal portion 8. At the perimeter of the disk 9 and on the under side thereof in opposed relation to the shanks 10, the lugs or projections 12 are formed.

13 designates the tie string or tape, to one end of which a ring or loop is attached, said loop being permanently engaged under one of the arms 11 between the same and the body portion of the disk 5.

In the use of the device, the disk 5 is arranged centrally upon the package of letters, papers or other articles, with its convex surface in engagement thereon, whereby it is understood that the peripheral edge of said disk will be out of contact with the surface of the package. The string or tape 13 is then passed in one direction around the package and turned around the spaced vertical portions of the shanks 10, said string being then extended at right angles around the other dimension of the package and the terminal thereof wrapped around the spaced shanks. As the string or tape accumulates upon the shanks 10, the projections or lugs 12 will bear with increasing pressure upon the string so that the extremity of said string will be securely held in connection with the metal tie element.

From the above description, taken in connection with the accompanying drawing, it is believed that the construction, manner of use and several advantages of the invention will be clearly and fully understood. The package of envelopes or other articles may be quickly and tightly bound together by means of the present invention and without necessitating the tying of knots in the string or tape. Owing to the fact that only the convex portion of the metal disk engages upon the package, the paper will not be torn or otherwise mutilated in the transmission of the package through the mails. The entire device may be as readily removed from the package and said device subsequently used

for similar purposes. It is apparent that the device can be manufactured in various sizes to be employed for different purposes, and that the disk constituting the body of the device may be of any desired shape or form.

While the preferred construction and arrangement of the several structural features of the device is shown, it is to be understood that the same is susceptible of considerable modification within the spirit and scope of the invention as claimed.

It will, of course, be manifest that when the device is to be used for the purpose of tying up metal sheets or other relatively heavy articles, flexible wire or chain is employed in lieu of the tape 13. In case the head 9 is subjected to pressure and bent downwardly within the dished portion of the disk 5, said head may be readily forced upwardly by inserting a nail or other like element through the central opening in the disk surrounded by the flange 7.

What is claimed is:—

1. A package tie including a sheet metal disk having a concavo-convex body portion, a head spaced from the concave face of the disk, shanks fixed to said head and having arms projecting outwardly in relatively opposite directions and secured to the outer edge portion of the disk, said head being provided on its under side with projections in opposed relation to said arms, and a tie string permanently attached to one of said arms and adapted to have its extremity wound about said shanks beneath the head,

the projections on said head having frictional bearing engagement upon the tie string.

2. A package tie including a metal disk having a concavo-convex body portion, a concentrically disposed head arranged in spaced relation to the concave face of the disk, spaced shanks secured to the under side of said head and having arms projecting laterally in opposite directions and secured at their extremities to said disk to sustain the head in spaced relation to the disk, said head being provided upon its under side with projections opposed to the respective shank arms for frictional bearing engagement upon a tie string wound about said shanks.

3. A bundle tie including a metal disk having a concavo-convex body portion and a straight horizontal marginal portion, a concentrically disposed head, spaced shanks fixed at one of their ends to the under side of the head and having arms projecting upwardly in relatively opposite directions and fixed at their extremities to the marginal portion of the disk to sustain the head in spaced relation to said disk, a tie string permanently connected to one of said arms, said string being adapted to be wound about said spaced shanks beneath said head and the projections on the head having frictional bearing engagement with the string.

MRS. ANNA MATT,
Administratrix of the estate of Albert E. Matt.
